(57) **CLAIM**

The ornamental design for a water supplying machine for endoscope, as shown and described.

DESCRIPTION

FIG. 1 is a perspective view from upper and right side of a first embodiment of a water supplying machine for endoscope, showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken lines shown in the drawing depict portions of the water supplying machine for endoscope that form no part of the claimed design.

The broken lines shown in the drawing depict portions of the water supplying machine for endoscope that form no part of the claimed design.
